US0D1110204S

(12) **United States Design Patent** (10) **Patent No.:** **US D1,110,204 S**
(45) **Date of Patent:** **** Jan. 27, 2026**

(54) **ELECTRIC VEHICLE**

(71) Applicant: **SHENZHEN ZHIMAHUAERKAI TECHNOLOGY CO., LTD.,**
Guangdong (CN)

(72) Inventor: **Qi Yi**, Shenzhen (CN)

(73) Assignee: **SHENZHEN ZHIMAHUAERKAI TECHNOLOGY CO., LTD.**, Shenzhen (CN)

(**) Term: **15 Years**

(21) Appl. No.: **29/932,487**

(22) Filed: **Mar. 14, 2024**

(51) LOC (15) Cl. **12-12**

(52) U.S. Cl.

USPC **D12/131**

(58) **Field of Classification Search**

(57) **CLAIM**

The ornamental design for an electric vehicle as shown and described.

DESCRIPTION

FIG. 1 is a left side view of an electric vehicle showing my new design;

FIG. 2 is a right side view thereof;

FIG. 3 is a rear view thereof;

FIG. 4 is a front view thereof;

FIG. 5 is a top view thereof;

FIG. 6 is a bottom view thereof;

FIG. 7 is a perspective view thereof;

FIG. 8 is a left side view of the electric vehicle in a folding state;

FIG. 9 is a right side view thereof;

FIG. 10 is a rear view thereof;

FIG. 11 is a front view thereof;

FIG. 12 is a top view thereof;

FIG. 13 is a bottom view thereof; and,

FIG. 14 is a perspective view thereof.

The broken lines indicate portions of the electric vehicle that form no part of the claimed design.

1 Claim, 14 Drawing Sheets
